[57] ABSTRACT

An automatic doffing apparatus adapted for use with an open end spinning machine having a plurality of spinning units arranged in side-by-side relation, for doffing full packages one by one from the respective spinning units during operation of the spinning machine while travelling along the front face of the spinning machine. The apparatus comprises a rotary doffer for disengaging the full package from a traversing roller, domounting the full package from a bobbin holder and then mounting an empty bobbin in the bobbin holder; and a cutting and suction device for cutting a spun yarn between the traversing roller and a take-up roller and lapping one of the cut yarn ends around the empty bobbin.

AUTOMATIC DOFFING APPARATUS

BACKGROUND OF THE INVENTION

1. Field of the Invention

This invention relates to an automatic doffing method and apparatus adapted for use with an open end spinning machine of the type in which a yarn is spun from a staple fiber and the spun yarn is directly taken up to form a package.

2. Description of the Prior Art

An apparatus for automatically doffing a package of yarn wound on a bobbin is presently known and used in a quick traverse winder (normally called winder). The winder with auto-doffer is basically designed such that each of winding units is circulated, that the winding unit is not provided with a draft or drawing mechanism and the rewinding yarn is drawn in a free state and that the feed of the yarn is readily interrupted on interruption of the winding operation. Therefore, the conditions that the feed of the yarn can be stopped without causing any detrimental effect when the full package is to be doffed from the winder and that the doffing operation can be carried out at a predetermined position of the winder, are very advantageous for the automatic doffing of the package.

However, in case of an open end spinning machine in which a yarn is constantly spun from a fibrous material at a fixed speed and the resultant spun yarn is taken up in the form of a cheese, the automatic doffing of the cheese or package must be carried out under conditions substantially different from those in case of the winder, by reason of the following facts:

- a. each of a plurality of spinning units arranged side-by-side does not move like the traverse winder,
- b. the spun yarn is continuously delivered even during the doffing operation, and
- c. the yarn is wound continuously even during the doffing operation.

SUMMARY OF THE INVENTION

The present invention relates to an automatic doffing in the open end spinning machine. According to the invention, each of a plurality of full packages is sequentially automatically demounted and replaced by an empty bobbin without necessitating interruption of the spinning operation even under such conditions and restrictions set forth above, whereby the doffing operation which has been carried out manually by two or three workers, can be achieved mechanically and automatically.

According to one aspect of the invention, there is provided an automatic doffing apparatus for use with an open end spinning machine having a plurality of spinning units arranged in side-by-side relation, for doffing full packages from the respective spinning units one by one while travelling along the front face of said spinning machine during operation of the same, said apparatus comprising a rotary doffer including means for releasing the package holding action of each bobbin holder of the spinning machine, a package receiving plate for receiving the package from said bobbin holder and a catcher for feeding an empty bobbin to said bobbin holder, said rotary doffer being rotated one complete turn about a horizontal shaft during every cycle of operation for demounting the package from the bobbin holder and mounting an empty bobbin in said holder; and cutting and suction means including

a cutter for cutting the spun yarn and suction nozzle for temporarily sucking the cut yarn end leading to the spinning unit at a speed corresponding to the spun yarn delivery speed and lapping said cut yarn end around the empty bobbin. By doffing the packages automatically sequentially from the spinning machine during its operation while moving the main body of the above-described doffing apparatus, it becomes possible to save labor, to automatize the doffing operation, to enhance productivity and to reduce production costs.

According to another aspect of the invention, there is provided an automatic doffing method in an open end spinning machine having a plurality of spinning units arranged in side-by-side relation, said method comprising moving a movable unit having a rotary doffer including a package receiving plate, and a cutter for cutting a spun yarn, along the front face of the spinning machine while rotating said rotary doffer; cutting the spun yarn between a winding drum and a take-up roller; disengaging a package from the winding drum and receiving said package by said package receiving plate from a bobbin holder of said spinning unit; discharging the package from said package receiving plate incident to rotation of said rotary doffer; engaging the cut yarn end leading to the spinning unit around the empty bobbin being held by said rotary doffer and mounting said empty bobbin in said bobbin holder; a cycle of said doffing operation being effected during one complete rotation of said rotary doffer.

The present invention will be described in detail hereinafter with reference to the embodiments thereof shown in the accompanying drawings.

BRIEF DESCRIPTION OF THE DRAWINGS

- 35 FIG. 1 is a perspective view showing the outline of one of spinning units of an open end spinning machine;
- 40 FIG. 2 is a side view illustrating the essential portions of the open end spinning machine and an embodiment of the automatic doffing apparatus according to the present invention;
- 45 FIGS. 3a - 3e are a set of diagrams illustrating, in side elevation, the operation of the spun yarn cutting and suction device;
- 50 FIGS. 4 and 5 are a plan view and a side view showing the essential portion of the spun yarn cutting and suction device respectively;
- 55 FIGS. 6 and 7 are a side view and a plan view of a rotary doffer respectively;
- 60 FIGS. 8 and 9 are a set of side views illustrating the reversal mechanism for the empty bobbin mounting catcher respectively;
- 65 FIG. 10 is a side view showing the details of the reversal mechanism;
- 70 FIG. 11 is a side view of the reversal mechanism looking in a direction of XI-XI of FIG. 7;
- 75 FIGS. 12a - 12d are a set of diagrams illustrating, in side elevation, the doffing operation of the rotary doffer step-by-step sequentially;
- 80 FIGS. 13a - 13e are a set of diagrams illustrating, in side elevation, the empty bobbin mounting operation of the rotary doffer step-by-step sequentially;
- 85 FIG. 14 is a schematic side view illustrating the relative motion of the rotary doffer and an empty bobbin feed nipper;
- 90 FIGS. 15 and 16 are a side view and a front view of the empty bobbin feed nipper respectively;

FIG. 17 is a fragmentary enlarged perspective view of a device for individually feeding empty bobbins;

FIGS. 18 and 19 are schematic front views showing, in cross-section, the outlines of two different embodiments of the empty bobbin delivery device respectively;

FIGS. 20, 21 and 22 are a sectional side view, a front view and a plan view briefly showing a laterally shifting device for empty bobbins respectively;

FIGS. 23 and 24 are a side view and a front view schematically showing the outline of the transmission system for the respective elements, respectively;

FIGS. 25 and 26 are a side view and a sectional view illustrating the relative position of the rack and the pinion in the transmission system respectively;

FIG. 27 is a side view showing the relative position of the rack and the pinion of FIG. 25, with said rack extended longitudinally;

FIG. 28 is a side view of another embodiment of the rotary doffer;

FIG. 29 is a plan view of the rotary doffer shown in FIG. 28;

FIGS. 30a - 30d are a set of diagrams corresponding to the diagrams of FIGS. 12a - 12d and illustrating, in side elevation, the doffing operation of the rotary doffer of FIG. 28 step-by-step sequentially; and

FIGS. 31a - 31e are a set of diagrams corresponding to the diagrams of FIGS. 13a - 13e respectively and illustrating the empty bobbin mounting operation of the rotary doffer of FIG. 28 step-by-step sequentially.

DESCRIPTION OF THE PREFERRED EMBODIMENTS

FIG. 1 shows a spinning unit of an open end spinning machine embodying the present invention, in which reference numeral 1 designates a spinning part including a feed roller, a fiber opening mechanism, a rotary spinning chamber and a yarn outlet tube, by which a sliver F from a can C is spun into a yarn; 2 a spun yarn take-up roller; 3 a grooved traversing roller; 4 the spun yarn; 5 a bobbin holder yieldably holding a bobbin 10 by a longer arm 21 and a shorter arm 22; and 6 a yarn package or cheese formed by winding the spun yarn on the bobbin 10. As is known, the open end spinning machine generally comprises a plurality of the above-described spinning units arranged in side-by-side relation.

The automatic doffing apparatus according to the present invention is designed such that it performs the operations of demounting the packages of a predetermined amount of spun yarn, i.e. the full package 6, from the respective spinning units and mounting empty bobbins 10 in the resultant vacancies automatically sequentially according to a predetermined program, while moving along the front face of an open end spinning machine of the type described above, without interrupting the spinning operation of each spinning part 1. The main body 20 of the automatic doffing apparatus of the invention comprises the following elements:

1. Yarn cutting and suction device,
2. Rotary doffer for dismounting full packages from the spinning machine and mounting empty bobbins thereon,
3. Bobbin transferring device, and
4. Transmission system for the rotary doffer.

Yarn Cutting and Suction Device

The yarn cutting and suction device serves to cut, prior to doffing, the spun yarn 4 extending to the package 6 and to suck successively thereafter the spun yarn 4 being delivered from the spinning part 1 towards an automatic doffer to be described later, while the package 6 is being doffed, so as to facilitate the lapping of the spun yarn 4 on the empty bobbin 10, and the construction thereof is briefly shown in FIGS. 3a - 5. As shown, an assembly 14 comprising a cutter 11, a suction nozzle 12 and a V-shaped yarn guide 13, is mounted on one end of an arm 15 which is rotatable about a shaft 16 through a predetermined angle. The cutter 11 is operated upon excitation of a solenoid 17 and the suction nozzle 12 is connected to a vacuum source 19 through a flexible tube 18. This assembly is normally held in a position indicated by the phantom line in FIG. 3a but angularly displaced towards the spinning machine 7 by being caused to make a pivotal movement about the shaft 16, and placed in a position indicated by the solid line, when the main body 20 is located opposite to a specific spinning unit for doffing the package 6 but before said package 6 is doffered by said main body. The spun yarn 4 is led towards the cutter by the yarn guide 13 at its length between the take-up roller 2 and the traversing roller 3, and pinched between the blades of the cutter 11. Immediately thereafter, the solenoid 17 is excited and the spun yarn 4 is cut by the cutter. At the same time, the cut end of the yarn leading to the traversing roller 3 is taken up by the package 6. The cut end of the yarn leading from the take-up roller 2 is sucked into the suction nozzle 12, so that the spun yarn 4 delivered from the spinning part 1 is continuously sucked into the suction nozzle 12 as a cut yarn S. The assembly 14 is displaced from the solid line position to the phantom line position under such condition (FIG. 3a). The yarn delivered from the spinning part 1 is continuously sucked into the suction nozzle 12 while the assembly 14 is held in the retreated position or the phantom line position. In FIG. 5, reference numeral 31 designates a blow nozzle from which air is blown to direct the cut end of the yarn towards the space between the empty bobbin 10 and the traversing roller 3 during the operation of mounting the empty bobbin 10 in the bobbin holder 5, which will be described later, so as to ensure positive lapping of the yarn end on said empty bobbin 10.

Rotary Doffer

The rotary doffer, which constitutes the main portion of the automatic doffing apparatus of the instant invention, comprises a cam plate 23 for opening and closing one of the arms 21 of the bobbin holder 5, a package receiving plate 24 for receiving the package 6 between the arms 21, 22 and transporting the same to a predetermined position, a guide plate 25 or gutter for guiding the package to a discharge end and a catcher 26 for mounting the empty bobbin 10. These members are rotated around a horizontal shaft 27 as a unitary assembly, and during one revolution of the assembly, the arm 21 of the bobbin holder 5 is opened by the cam plate 23 and the package 6 is transferred onto the package receiving plate 24 and carried thereon towards a conveyor 8 provided at a predetermined position. Immediately thereafter, the empty bobbin 10 retained by the catcher 26 is placed between the arms 21, 22 which are now opened, and then the arms 21, 22 are closed to hold the empty bobbin 10 therebetween. The bobbin

holder 5 is moved downwards by lowering means, not shown, provided in the doffing apparatus, and placed again in the yarn winding position.

As shown in FIGS. 6 and 7, the rotary doffer, which is generally indicated by reference numeral 30, is rotated full turn on every shifting of the same one pitch of the spinning units 1 and completion of every cycle of operation by transmission means to be described later. The package receiving plate 24 has an arcuate cross-sectional shape and extends from one side of a central shaft 27 about which the rotary doffer 30 is revolved, and a gutter 25 extends in the opposite direction from the arcuate inner surface of said package receiving plate 24. The empty bobbin mounting catcher 26 is disposed opposite to the gutter 25. The package receiving plate 24 and the catcher 26, as shown in FIG. 7, are arranged such that the center line of the catcher 26 is located a distance H offset from the center line A of the package receiving plate 24 at right angles to the shaft 27, in the direction of travel of the main body 20. The distance H is the distance of travel of the main body 20 during the period in which the package 6 between the arms 21, 22 of the bobbin holder 5 is received by the package receiving plate 24 and the empty bobbin 10 is mounted between the arms 21, 22 by the catcher 26. This state is shown also in FIG. 29. The cam plate 23 is required to hold the arm 21 in the same position during travel of the automatic doffing apparatus along the front face of the spinning machine and while rotating along with the rotary doffer 30. Therefore, the cam plate 23 has an outwardly convexed curved surface extending from the point at which said cam plate is brought into contact with the arm, to the point at which the same is disengaged from said arm (FIGS. 7 and 29). The empty bobbin mounting catcher 26 is pivotable through an angle of about 180° as shown in FIGS. 8, 9 and 10.

The operation of the rotary doffer 30 during its full turn will be described step-by-step with reference to FIGS. 12a - 12d and FIGS. 13a - 13e. First of all, the package 6 to be doffed is lifted by the top end of the package receiving plate 24 during a constant speed rotation of the rotary doffer 30 about the shaft 27. At the same time, the arms 21, 22 are pivotally moved upwards in a snap about a pin 5a under the pushing action of the package receiving plate 24, to their highest positions and thus disengaged from the traversing roller 3 and the package receiving plate 24 is positioned below the package 6 in contact therewith. In this case, the cam plate 23 abuts against the inner surface of the arm 21 and urges said arm outwardly, so that the package 6 is released from the arms and drops on the package receiving plate 24. The rotary doffer 30 continues its rotation and when the gutter 25 is brought into a horizontal position, the package 6 on the package receiving plate 24 rolls onto the gutter under the force of inertia created by the rotation of the rotary doffer 30. As the rotary doffer 30 further rotates, the gutter 25 is inclined, so that the package on said gutter is accelerated and rolls on an auxiliary guide 28 to ride on the conveyor 8 which extends parallel to the spinning machine 7 at a level slightly lower than the shaft 27 of the doffer 30. The auxiliary guide 28 is disposed between the guide plate 25 and the conveyor 8, and operatively connected with the catcher 26 so that it may be shifted from a stretched position of FIG. 8 to a retracted position of FIG. 9 incident to rotation of the catcher 26.

after the package 6 has been transferred onto the conveyor 8 in the manner described, the rotary doffer 30 rotates further and the catcher 26 catches the empty bobbin 10 which is held still at a point on the rotational locus B of said catcher 26 (FIG. 14). The catcher 26 is turned back immediately after catching the empty bobbin, with its open side facing backwards. Such reversal of the catcher 26 as shown in FIGS. 8 - 10 is necessary to enable the empty bobbin 10 to be readily released from said catcher when said empty bobbin is placed between the arms 21, 22 incident to rotation of the rotary doffer 30, and thereby to enable said catcher to continue its rotary motion.

The catcher reversal mechanism is constructed as described hereinbelow: Thus, as shown in FIG. 7, a supporting member 25b is fixedly mounted on the shaft 27 on one side of the gutter 25, i.e. on the side closer to the cam plate 23, and the lower end thereof as viewed in FIG. 7 is bifurcated to provide bearings 25c, 25d. These bearings 25c, 25d support a shaft 35. A catcher arm 36 projects from the shaft 35 at right angles thereto and a crescent-shaped plate 36a is connected to the outer end of said arm. A pair of U-shaped catcher springs 26a, 26b are connected to the opposite ends of the plate 36a, with the outer ends thereof in alignment with each other. A collar 27a is loosely mounted on the shaft 27 outwardly of the supporting member 25b and an arm 27b projects from the outer peripheral surface of said collar 27a, with its end extending through a pin 32 which is provided an end portion of an egg-shaped cam gear 34. A coil spring 27c is mounted around the arm 27b between the pin 32 and the collar 27a, so that the arm 27b may be displaced snapingly from a solid line position to a phantom line position in FIG. 10 under the effect of the coil spring 27c. The cam gear 34 is rotatable on the shaft 34a and arms 34b, 34c are connected to said shaft 34a in the form of bell crank. The pin 32 mentioned above is provided at the end of the arm 34b, while a pin 39 is provided at the end of the arm 34c. The gear 34 is in meshing engagement with a pinion 33 which is fixedly mounted on one free end of the shaft 35. On the other end of the shaft 35 is mounted another pinion 35a for meshing engagement with a gear 37 mounted on a supporting shaft 38 for the auxiliary guide 28.

After the catcher 26 has caught the empty bobbin 10, the pin 32 of the reversal mechanism abuts, for instance, against a fixed pin which is stationary relative to the rotary doffer 30, whereby the cam gear 34 is rotated through a predetermined angle, causing the pinion 33 to rotate the half of its full turn, so that the catcher arm 36 is turned about 180°. Thus, the open side of the catcher 26 is directed in a reverse direction. At the same time, the gear 37 is rotated about half of its full turn by the pinion 33, causing the auxiliary guide 28 to rotate through the shaft 38, so that the guide 28 is turned through a slit formed in the gutter 25 and placed on the back side of said gutter 25 as shown in FIG. 9. Because of such arrangement as above described, it is possible to prevent the auxiliary guide 28 from collision against a portion of the spinning machine 7 during rotation of the rotary doffer 30 subsequent to transfer of the package 6 onto the conveyor 8 by way of the auxiliary guide 28. The catcher 26 is reversed in the manner described above during its travel from the position where it catches the empty bobbin 10 to the position of the bobbin holder 5, and then mounts the

empty bobbin between the arms 21, 22 of said pin holder.

When the empty bobbin 10 has been brought to the position of the bobbin holder 5 to be mounted therein, the cam plate 23, which has been expanding the arms of said bobbin holder 5 is disengaged from said bobbin holder due to continuous rotation of the rotary doffer, the said holder 5 is returned to its closed position under its own resiliency, thereby holding the empty bobbin in a predetermined position. Once the empty bobbin 10 has been mounted in the bobbin holder 5 in the manner described above, it will not be readily demounted therefrom even when subjected to a force perpendicular to the axis of said empty bobbin. Therefore, even though the catcher 26 moves by being carried by the rotary doffer 30, the empty bobbin 10 remains between the arms of the bobbin holder 5 against the clamping force of the catcher 26 and the catcher moves rotationally upwardly, leaving said empty bobbin 10 in the bobbin holder 5. Thereafter, the open side of the catcher 26 is directed in the direction of rotation of the rotary doffer 30 by the engagement of the pin 39 with another projection (not shown) provided on the main body 20, and at the same time, the auxiliary guide 28 is placed in its retracted position in contact with the gutter 25. Thus, one cycle of package doffing operation for one spindle (one spinning unit) is completed. Since the main body 20 of the doffing apparatus continuously travel along the front face of the spinning machine 7 though slowly, when the rotary doffer 30 has made a full turn and completed the package doffing operation for one package, the package receiving plate 24 is already in a position adjacent the undersurface of the package of the next spinning unit and the doffing machine starts the above-described doffing operation for said spinning unit. In the manner described above, the packages of all spinning units arranged side-by-side are doffed and the empty bobbins 10 are mounted continuously sequentially.

Bobbin Transferring Device

This device serves to feed the empty bobbin 10 to a point on the locus of rotation B of the catcher 26 of the rotary doffer 30 to enable the catcher 26 to grasp said empty bobbin, and is composed of a rod 40 reciprocatable over a predetermined stroke, an empty bobbin nipper 41 provided at an end of said rod 40, a solenoid 42 mounted on said rod for opening and closing said nipper 41, a mechanism (FIGS. 14 - 16) to cause a reciprocal motion of said rod 40 and an empty bobbin feed mechanism (FIGS. 16 - 22) for individually feeding the empty bobbins 10 to said nipper 41. A hopper 50 (FIG. 2) accommodating a plurality of empty bobbins 10 therein has a peripheral groove in which a conveyor 51 (hereinafter referred to as interblock conveyor) is received. The conveyor 51 includes a plurality of block pieces 51a arranged side-by-side at an interval corresponding to the width of the bobbin and continuously rotated as by a chain 80 (FIG. 23). The bobbins 10 in the hopper 50 are individually fed into the interspace of the adjacent block pieces. Namely, the bobbins 10 are individually delivered from the hopper upwardly by the conveyor 51, and dropped in a groove 52 formed in the hopper below said conveyor. The bobbin placed in the groove 52 is shifted axially by laterally shifting means 53 and then transferred into the nipper 41 which is then located in a position to receive said bobbin. The nipper 41 consists of forked grasping arms 41a, 41b.

Upon receiving the bobbin, one of the grasping arms 41b is pivoted for grasping by the solenoid 42 which is excited in response to a signal from the laterally shifting means 53, and thus the empty bobbin is held by said arms therebetween. The mechanism for causing a reciprocal motion of the rod 40 comprises a cam 43 rotatable about a shaft 43a, a cam layer 44 which makes an angular displacement about a shaft 44a in contact with said cam 43, a segment gear 45 fixed on the shaft 44a and rotatable with said shaft, a small pinion 46 rotatable about a shaft 46a in meshing engagement with the gear 45 and a large pinion 46 coaxial with said pinion 46b and meshing with a rack 47 provided on said rod 40. The rod 40 is caused to reciprocate through the members 44, 45, 46a and 46 by the cam 43 which makes a half turn when the bobbin 10 is grasped between the arms 41a, 41b, whereby the nipper 41 is shifted from a position indicated by the solid line to a position indicated by the phantom line, i.e. the position lying on the locus of rotation B of the catcher 26, in FIG. 14. Another pinion 46 is identical with the aforesaid pinion 46 and is a follower guide pinion. The cut yarn S being sucked into the suction nozzle 12 is lapped around the empty bobbin 10 at this time (FIGS. 3c and 14). With the empty bobbin 10 being held in that position, the catcher 26 of the rotary doffer 30 approaches the nipper 41 and carries the empty bobbin 10 away from said nipper. In order to facilitate the transfer of the empty bobbin 10, the nipper is so constructed as to hold the opposite end portions of the bobbin by the forked arms as shown in FIG. 16, while the catcher 26 of the rotary doffer 30 is so constructed as to grasp the mid portion of the bobbin.

The laterally shifting means 53 includes a shifting projection provided on a belt which is engaged around a pair of rollers, and said projection passes through a slit formed in the side wall of the groove 52 to shift the bobbin 10 in a lateral direction. Alternatively, any other means may be employed for this purpose, which is suitably selected by those skilled in the art. Likewise, two conveyors arranged side-by-side as shown in FIG. 19 may be used instead of the conveyor 51 shown in FIG. 18. In this case, the grooves 52 formed below the respective conveyors should be aligned with each other and the length of the slit formed in the side walls of the grooves should be made longer. It is also necessary to rotate the conveyors in different phase relation so that two bobbins will not concurrently be placed in the grooves 52. In either case, it is preferable that the operation of laterally shifting the bobbin is associated with the rotational motion of the doffer.

Rotary Doffer Rotating Device

A device for rotating the rotary doffer one complete turn correctly during its movement over one pitch of the spinning units will be described with reference to FIGS. 23 - 27. A rack rail 55 is extended along the upper face of the spinning machine 7 and the main body 20 of the doffing apparatus is moved, with a pinion 56 mounted thereon in engagement with the rack of said rack rail 55. The number of teeth of the pinion 56 is so selected that the pinion makes one or two revolutions in meshing engagement with the rack 57 during its travel over one pitch of the spinning parts 1. The arrangement is made, for instance, such that the shaft 27 of the rotary doffer 30 is rotated by the pinion 56 through intermediate gears 70, 71 and shafts 72, 73 as shown in FIGS. 23 and 24. Thus, it will be under-

stood that the rotary doffer 30 makes one revolution accurately with the same phase for every spinning unit, and the mechanisms operatively connected to the shaft of the rotary doffer 30 are also operated accurately from said shaft in synchronism with said rotary doffer according to the predetermined program. The conveyor 51 is driven from the shaft 27 through a chain 76 engaged around a gear 74 on the shaft 27 and a gear 75 of the conveyor 51, and a chain 80 engaged around other gears 75a, 77, 78 and 79 of said conveyor. Where a frame or spring piece of the spinning machine is present between the spinning units and the pitch of the spinning units is varied thereby, the teeth of the rack rail 55 are removed over a length corresponding to the width of said frame or spring piece as shown in FIG. 25, so that the rotation of the pinion 56 may be interrupted over said length of the rack rail. In this case, a stud 60 is provided on the rack rail 55 at the terminal end of the non-toothed portion 58 immediately before the teeth 59, while an auxiliary tooth 62 projecting outwardly of the teeth 61 is provided on the pinion 56, so as to avoid strong collision between said pinion 56 and said teeth 59. The auxiliary tooth 62 is provided at such a location that the pinion 56 starts rotating when said auxiliary tooth 62 abuts against the stud 60. While in the embodiment shown, the rack rail 55 is provided above the spinning machine, it may be provided at a lower side of the spinning machine.

Operation

The automatic doffing apparatus of the invention operates as follows: First of all, the main body 20 of the apparatus is led to a specific open end spinning machine to be doffed and is caused to travel at a predetermined speed along the front face of said spinning machine. The rotary doffer 30 starts to revolve due to the engagement between the rack 57 and the pinion 56, while performing the package doffing operation for the first spinning unit. At the outset of the doffing operation, the assembly 14 of the cutter 11, the suction nozzle 12 and the yarn guide 13 moves forward to the solid line position of FIG. 3a and the spun yarn 4 extending between the take-up roller 2 and the traversing roller 3 is cut by the cutter 11 (FIG. 3b). Then, the assembly 14 moves back to the phantom line position while sucking the spun yarn 4, being delivered from the spinning part 1, into the suction nozzle 12 (FIG. 3c). Incident to rotation of the rotary doffer, the outer edge of the package receiving plate 24 strikes the arm 21 and lifts the bobbin holder 5 (FIG. 2a). When the package receiving plate 24 is located below the package 6 (FIG. 12b), the cam plate 23 engages the bobbin holder 5 urging the arm 21 to open relative to the arm 22, and the package 6 drops on the receiving plate 24 (FIG. 12c). The assembly 14 completes its backward movement during this period and the empty bobbin laterally shifting means 53 (FIGS. 21 and 23) is actuated to transfer the empty bobbin 10 into the nipper 41. The package 6 on the package receiving plate 24 is carried towards the conveyor 8 incident to rotation of the rotary doffer 30 (FIGS. 12d and 13a), during which period the nipper arms 40 are elevated and holds the empty bobbin still on the locus of rotation B of the catcher 26 (FIG. 3c). When the package 6 on the package receiving plate 24 is lifted to the highest position, it starts to roll onto the gutter 25 from said receiving plate 24 and then onto the conveyor 8 by way of the auxiliary guide 28, and thus the doffing operation is

completed. Successively thereafter, the catcher 26 moves on the locus B and grasps the empty bobbin 10 being held by the nipper 41 (FIG. 13b). Upon completion of the transfer of the empty bobbin 10 from the nipper 41 to the catcher 26, said nipper 41 returns to its original position. Then, the catcher 26 is turned back as described previously, whereby the auxiliary guide 28 is retracted and the open side of the catcher faces backwards (FIGS. 9 and 13c). The catcher continues its rotational movement in this state, towards the bobbin holder 5. In this case, the assembly 14 including the suction nozzle 12 is also moved toward the spinning machine, whereby the breakage of the cut yarn S extending between the suction nozzle 12 and the empty bobbin 10 is prevented. When the catcher 26 holding the empty bobbin 10 reaches the bobbin mounting position between the arms of the bobbin holder 5, the holder 5 is disengaged from the cam plate 23 and the arms of said holder are closed to hold the empty bobbin 10 therebetween (FIG. 13d). As a result, the empty bobbin 10 is removed from the catcher 26 incident to rotation of the rotary doffer 30, and thus the transfer of the empty bobbin 10 from the catcher 26 to the bobbin holder 5 is completed. Thereafter, the catcher 26 continues its rotational movement upwardly (FIG. 13e). In this case, the bobbin holder 5 is moved down to the winding position by depressing means (not shown) provided in the main body 20 of the doffing apparatus. In this case, the cutter 11 of the assembly 14 is actuated to cut the cut yarn S extending between the bobbin 10 and the suction nozzle 12 and the cut end of the yarn is directed into between the empty bobbin 10 and the traversing roller 3 by a jet of air ejected from the blow nozzle 31, whereby the yarn end is lapped around the empty bobbin. Then, the assembly is moved back and the doffing operation is completed by this step. The doffing apparatus starts another cycle of the doffing operation for the next adjacent spinning unit successively thereafter.

40 The doffing apparatus of the invention is preferably provided with means by which a package of a diameter smaller than a predetermined diameter is detected prior to the doffing operation and a clutch is actuated to skip the particular spinning unit involving such an undersized package, but such means will not be described herein.

Another Embodiment of the Rotary Doffer

The rotary doffer described above is operative such that the package received by the package receiving plate is transferred into the gutter incident to rotation of the doffer and then delivered onto the conveyor 8 through the auxiliary guide. However, it is desirable that the package received by the package receiving plate is more quickly discharged onto the conveyor. Such an arrangement will be described with reference to FIGS. 28 and 29 hereunder: A rotary doffer according to this embodiment includes a rotary body 82 fixedly mounted on a drive shaft 81 and a stationary cam 83 held stationary relative to said rotary body 82, said drive shaft 81 being rotated one complete turn by transmission means during its movement over one pitch of the spinning units as in the preceding embodiment.

60 The rotary body 82 fixedly mounted on the drive shaft 81 has a crescent-shaped cross section and is provided at portions thereof with a bracket 80 for mounting a package receiving plate 85 and a guide plate, i.e. a gutter 86 for delivering the package 6 to the conveyor

8. It is also provided on one side thereof with a cam plate 84 for opening and closing the bobbin holder 5. An auxiliary guide 87 is connected to one end of the guide plate 86 for bridging the space between the rear end of said guide plate and the conveyor 8. As in the preceding embodiment, this auxiliary guide plate 87 is operated by an empty bobbin catcher 88 such that it is stretched out incident to reversal of said catcher 88 and then retracted. The catcher 88 is spaced by a distance H from the center line A of the package receiving unit perpendicular to the drive shaft 81, in the direction of travel of the main body 20 of the automatic doffing apparatus, as in the preceding embodiment.

A reversal mechanism for the catcher 88 includes an egg-shaped gear 94 fixedly mounted on a shaft 105 for rotation therewith, said shaft 105 being integrally connected with the rotary body 82, and a gear 93 fixedly mounted on a shaft 95 and meshing with said egg-shaped gear 94, said shaft 95 being integral with the rotary doffer. An arm 96 extends from the shaft 95 at right angles thereto and a catcher 88 is connected to the end extremity of said arm 96. A pinion 106 is mounted on the shaft 105, which is in meshing engagement with a pinion 97 fixedly mounted on a rotary shaft 98 of the auxiliary guide 87. The gear 94 is provided with pins 91, 92. The pin 91 is operatively associated with a collar 107 by means of a spring 108, which collar 107 is loosely mounted on the rotary shaft 87. The arrangement is such that when either one of the pins 91, 92 abuts against a fixed projection (not shown) and being stationary relative to the rotary body 82, the gear 94 is rotated so that the gear 93 is rotated 180° to reverse the catcher 88 and at the same time the pinion 97 is rotated by the intermeshing pinion 106 to bring the auxiliary guide 87 into its retracted position along the guide plate 86.

On the other hand, the package receiving plate 85 is carried by the bracket 89 which is fixedly mounted on a shaft 99 rotatably carried on the rotary body 82. Thus, the package receiving plate 85 is pivotable about the shaft 99. The stationary cam 83, as shown in FIG. 29, is secured by means of arms 110 to a portion 109 of the main body 20 which is stationary relative to the rotary body 82, and loosely fitted to the rotary body 82. A cam lever 100 mounted on the shaft 99 is in sliding engagement with the cam surface of the stationary cam 83 having a heart-shaped profile, under the biasing force of a spring 101, whereby a rocking motion is imparted to said lever 100 and hence an orbital rotational motion is imparted to the package receiving plate 85 by the stationary cam 83 during rotation of the rotary body 82. By imparting the orbital rotational motion to the package receiving plate 85, there can be obtained such advantages that the distance of travel of the package 6 can be shortened and thereby the conveyor 8 can be located close to the open end spinning machine 7, and that the transfer time of the package 6 can also be shortened.

The doffing operation of the rotary doffer described above will be explained step-by-step with reference to FIGS. 30a - 30d. The doffing operation proceeds step-by-step from the state of FIG. 30a to the state of FIG. 30d in the order indicated by the arrows, the sequence of the doffing steps being the same as that of the doffing steps illustrated in FIGS. 12a - 12d. First of all, in FIG. 30a is shown the state in which the package 6 to be doffed is about to be lifted by the tip end of the package

receiving plate 85. The next step shown in FIG. 30b corresponds to the state of FIG. 12b, in which the package 6 is scooped and lifted up from the traversing roller 3 by the package receiving plate 85. The rotary doffer 82 continues to rotate from this state to the state shown in FIG. 30c in which the guide plate 86 is substantially horizontal. The rotational speed of the package receiving plate 85 becomes higher than that of the rotary body 82 and the guide plate 86, during this period, by the action of the stationary cam 83 and the cam lever 100, and the package is thrown out of the package receiving plate 85. Therefore, the package 6 rolls on the gutter under a positive rolling force imparted thereto by the package receiving plate 85. FIG. 30d shows the state wherein the package 6 is placed on the conveyor 8 positioned parallel to the spinning machine 7 at a level slightly lower than the axis of the drive shaft 81 after rolling on the guide plate 86 with acceleration given thereto by the throwing action of the package receiving plate 85 and the inclination of the guide plate 86. In this case, the auxiliary guide 87 provided at the terminal end of the guide plate 26 is stretched out to bridge the space between said guide plate 86 and the conveyor 8, providing for transfer of the package onto the conveyor 8.

Next, the manner of feeding an empty bobbin to the bobbin holder will be described step-by-step in sequence with reference to FIGS. 31a - 31e. The sequential steps shown in FIGS. 31a - 31e correspond to those of FIGS. 13a - 13e. First of all, FIG. 31a shows the state in which the empty bobbin 10 with the spun yarn 4 from the spinning part 1 engaged therearound is held still in a stand-by position on the locus of rotation of the empty bobbin mounting catcher 88 of the rotary body 82, upon completion of doffing of the full package 6. FIG. 31b shows the state in which the empty bobbin 10 is grasped by the catcher 88 upon further rotation of the rotary body 82. Immediately after the step of FIG. 31b, the catcher 88 is turned back as shown in FIG. 31c and the empty bobbin is mounted in the holder 5 upon further rotation of the rotary doffer 82 as shown in FIG. 31d. The catcher 88 is again turned back immediately thereafter, as shown in FIG. 31e. In this case, the auxiliary guide 87 is also turned back concurrently as is obvious.

According to this embodiment, the package receiving plate 85 is pivotable relative to the rotary body 82 and is rotationally moved at a varying speed, so that said package receiving plate may be caused to make a rotational motion at a speed faster than the rotational speed of the rotary body 82 during a part of period of one complete operating cycle. Therefore, it is possible to effect the transfer of the package 6 from the bobbin holder 5 onto the guide plate 86 and the transfer of the same from said guide plate onto the conveyor 8 at a faster speed and in a shorter period of time than in the preceding embodiment. In addition, when the package receiving plate 85 is on the side opposite to the bobbin holder 5, the tip end of said package receiving plate can be positioned inwardly of the normal position, which relieves the mounting conditions for the conveyor 8.

We claim:

1. In an apparatus for doffing full packages one by one from a plurality of spinning units, arranged side-by-side, of an open end spinning machine while travelling along the front face of said spinning machine, each of said spinning units having a bobbin holder for a holding

a bobbin to be wound by a spun yarn therearound to make the full package, the improvement comprising; a rotary doffer rotatable about a horizontal axis and having a mechanism for releasing said bobbin from said bobbin holder; a package receiving plate for receiving the full package released from said bobbin holder; a catcher for supplying an empty bobbin to said holder; cutting and suction mechanism including a cutter for cutting the spun yarn and for imparting suction forlapping the cut yarn end around said empty bobbin; and means for rotating said doffer about its axis, wherein a cycle of operation of dismounting the package from the holder and mounting the empty bobbin in said holder is effected during one complete turn of the doffer.

2. An apparatus according to claim 1, comprising a pinion rotatable about its axis for transmitting the rotation to said rotary doffer, said pinion being meshed with a guiding rack rail extending along the front face of the spinning machine for guiding the apparatus therealong.

3. An apparatus according to claim 1, wherein said bobbin releasing mechanism is a cam, the developed periphery of which is inclined in a direction opposite to the direction of travel of said apparatus.

4. An apparatus according to claim 1, wherein said rotary doffer further includes a gutter for guiding the package, received by the package receiving plate, in a package delivering direction.

5. An apparatus according to claim 4, wherein the center of the catcher is offset from the center of the gutter in a direction opposite to the direction of travel of the apparatus.

6. An apparatus according to claim 1, wherein said package receiving plate has its outer end portion curved in the rotating direction of the rotary doffer and pushes up the package from a winding drum at said end.

7. An apparatus according to claim 1, wherein means is provided to reverse the direction of said catcher.

8. An apparatus according to claim 1, wherein said cutter is provided with a V-shaped yarn guide for guiding the spun yarn.

9. An apparatus according to claim 1, wherein said cutting and suction mechanism is unitarily movable between a delivery roller and a winding drum from a position to cut the spun yarn to a position to lap the cut yarn end around an empty bobbin.

10. An apparatus according to claim 1, which further comprises means for feeding empty bobbins to the catcher.

11. An apparatus according to claim 10, wherein said empty bobbin feed means includes a nipper provided at its end for grasping the empty bobbin and a rod reciprocated towards and away from the moving path of the catcher.

12. An apparatus according to claim 11, wherein said empty bobbin feed means further includes a hopper for accommodating a number of empty bobbins, a conveyor for delivering said empty bobbins one by one from said hopper, and means for receiving the empty bobbin from said conveyor and carrying the same towards said nipper.

13. An apparatus according to claim 1, wherein said package receiving plate is rotatable non-synchronously with the rotation of a rotary body so as to quickly discharge the package received thereby.

14. A method of doffing full packages one by one from a plurality of spinning units, arranged side-by-side, of an open end spinning machine, said method comprising moving along the front face of said machine a movable assembly comprising a rotary body having a package receiving plate, and a cutter for cutting a spun yarn, while rotating said rotary body; cutting the spun yarn beneath a winding drum; releasing the engagement between a package and a winding drum to receive the package on the package receiving plate from a bobbin holder; discharging the package from the package receiving plate under inertia created by the rotation of the rotary body; lapping the cut yarn end around said empty bobbin being held stationary; and mounting said empty bobbin in said bobbin holder; a cycle of the above-described operations being effected during every full rotation of said rotary body.
